(57) **CLAIM**

The ornamental design for a Jesus-shaped corkscrew and bottle cap opener, as shown and described.

DESCRIPTION

FIG. 1 is a perspective view of a Jesus-shaped corkscrew and bottle cap opener showing my new design;

FIG. 2 is a front view thereof;

FIG. 3 is a rear view thereof;

FIG. 4 is a side view thereof; and,

FIG. 5 is a partial perspective view thereof, shown in an environment of use.

The broken lines depict environmental subject matter only and form no part of the claimed design.
